**PRACTICE GOLF BALL REMOVABLY
 TETHERED TO A MAT**
 Louis Fink, Reading, Pa.
 (4925 Collins Ave., Miami Beach, Fla.)
 Filed Aug. 23, 1963, Ser. No. 304,005
 5 Claims. (Cl. 273—198)

This invention relates generally to golf practice devices, and more specifically, to a golf swing practice device usable either indoors or outdoors on a floor or like supporting surface.

A primary object of the invention is to provide a golf practice device of the type indicated above which may be used for practice either indoors or outdoors, and one which is readily reversible for use either by left-handed or right-handed persons.

Another objective of importance of this invention resides in the provision of a golf practice device of the character indicated above, usable on a supporting surface, including a captive ball portion, wherein means is provided for selective height adjustment of the ball portion.

Yet another object is to supply a practice device of the stated character which may be used without danger of damage to the floor or supporting surface.

Still another object is to provide a swing practice device having means to absorb the shock of striking the captive ball portion with a golf club, whereby excessive wear is avoided and stability of position is accomplished.

General objectives of the invention include the provision of a golf swing practice device which is non-complex in construction and assembly, inexpensive to manufacture and sell, and relatively durable in use.

Other and further objects and advantages of the present invention will become apparent from a consideration of the following specification when read in conjunction with the annexed drawings, in which:

FIGURE 1 is a perspective view showing a first form of practice device constructed and assembled in accordance with the teachings of this invention, a portion of a golf club, and portions of the device being shown in dotted lines in operational positions;

FIGURE 2 is an enlarged, substantially medial cross sectional view of the device as seen in FIGURE 1;

FIGURE 3 is a top plan view of a portion of the device, partially in cross section along the line 3—3 of FIGURE 2, looking in the direction of the arrows;

FIGURE 4 is a detail sectional view taken substantially along the section line 4—4 of FIGURE 2, looking in the direction of the arrows;

FIGURE 5 is another detail view, in cross section, along the line 5—5 of FIGURE 4, looking in the direction of the arrow;

FIGURE 6 is a partial perspective view showing a modification;

FIGURE 7 is a disassembled perspective view, showing certain elements of the assembly of FIGURE 6;

FIGURE 8 is an enlarged, sectional view, taken substantially on the section line 8—8 of FIGURE 6, looking in the direction of the arrows;

FIGURE 9 is a partial perspective view showing the device as used by a right-handed golfer; and

FIGURE 10 is a view similar to FIGURE 9, showing the device as modified for use by a left-handed golfer.

Proceeding to a more detailed description of the invention, and referring initially to FIGURES 1—5, the invention is therein generally designated by character reference 20, and comprises a mat or base member 22 of generally rectangular form, having an upper side 24, an underside 26, and bevelled end edges 28. The mat 22 is preferably formed of plastic or other slip resistant

2

material having a coefficient of friction such that it is unlikely to slide when placed on a floor formed of wood, tile, or other common flooring material, and is of a dimension to resist such slippage.

5 At a selected location intermediate two ends of the mat and adjacent another end, the upper side 24 has a projecting strengthened portion 30 thereon, preferably of the substantially hour-glass form seen in FIGURE 3. Extending from the ends of the strengthened portion 30 are frusto-conical bosses 32, the portion 30 and bosses 32 being integral with the mat 22 or fixedly secured thereto. Each of the bosses 32 has a vertical opening 34 formed therein and extending fully through the bosses and the mat therebeneath, and the mat underside 10 15 20 25 30 35 40 45 50 55 60 65 70 75 80 85 90 What is claimed is:

1. A golf swing practice device adapted for use on a floor or like surface, the device comprising:
  - (a) a generally rectangular, flat mat element having an upper side and an underside;
  - (b) a substantially U-shaped pin member, having a bight portion and a pair of arms, the bight portion being positioned adjacent the underside of the mat and the pin arms extending through the mat and projecting vertically from the upper side thereof;
  - (c) elevation means about the pin arms adjacent the mat;
  - (d) a removable, flexible ball support including a support section and a projecting arm having an outer end;
  - (e) the support section having a pair of openings formed therein removably receiving the pin arms therethrough; and
  - (f) a ball member secured to the outer end of the arm.
2. A golf swing practice device as defined in claim 1 wherein said mat is formed of a slip resistant material.
3. A golf swing practice device as defined in claim 1 wherein the mat has a grass-like upper side.
4. A golf swing practice device adapted for use on a floor or like surface, the device comprising:
  - (a) a substantially rectangular, flat mat element having an upper side and an underside and having bevelled end edges;
  - (b) an inverted, substantially U-shaped pin member, having a bight portion and a pair of upstanding

arms, the bight portion being positioned adjacent the underside of the mat and the pin arms extending through the mat and projecting vertically from the upper side thereof;

- (c) means to permit the bight portion of the pin member to seat substantially flush with the mat underside;
  - (d) elevation means, comprising a pair of bosses, about the pin arms adjacent the mat;
  - (e) a removable, flexible, ball support including a support section and a projecting arm having an outer end;
  - (f) the support section having a pair of openings formed therein removably receiving the pin arms therethrough;
  - (g) a ball member secured to the outer end of the arm; and
  - (h) the support section having vibration absorbing openings formed therein.
5. A golf swing practice device as defined in claim 4, wherein:
- (a) said pin receiving openings in the support section are tapered from end to end.
